UNITED STATES PATENT OFFICE.

ARNOLD H. HOTTINGER, OF CHICAGO, ILLINOIS.

SPRAYING DEVICE.

Application filed April 3, 1925. Serial No. 20,323.

The invention relates to improvements in pneumatic sprayers, particularly paint sprayers such as the one disclosed in my copending application Serial No. 20,322, filing date 5 April 3, 1925.

The primary object of the invention is to provide a novel spraying device adapted to apply paints of a multiplicity of colors to surfaces such as those of ceramic tile to obtain 10 a mottled color effect.

A more specific object resides in the provision of a spraying device of the above character of novel means for mixing the differently colored paints in the spray head.

A further object is to provide a spraying device which can be adapted to either project a plurality of independent jets of paint or project one jet of paint in which a number of paints are partially mixed.

Ancillary objects and advantages will become apparent as the description proceeds.

In the accompanying drawings, Figure 1 is a plan view of a spraying device embodying the features of my invention.

Fig. 2 is a sectional view thereof taken substantially along line 2—2 of Fig. 1.

Fig. 3 is a view taken along line 3—3 of Fig. 1 of the front plate forming part of the spray head.

Fig. 4 is a front end view of the spraying device.

Fig. 5 is a front view taken along line 5—5 of Fig. 1 of the casing forming part of the spray head.

Fig. 6 is a rear view taken along line 6—6 of Fig. 1 of the casing forming part of the spray head.

Fig. 7 is a perspective view of the mixing cone.

Fig. 8 is a fragmentary sectional view of the means for controlling the supply of paint to the spray head.

While the invention is susceptible of various modifications and alternative constructions, I have shown in the drawings and will herein describe in detail the preferred embodiment, but it is to be understood that I do not thereby intend to limit the invention to the specific form disclosed, but aim in the accompanying drawings to cover all modifica-

tions and alternative constructions falling within the spirit and scope of the invention.

Referring to the exemplary embodiment of the drawings, the spraying device consists of a flat base plate 10 substantially rectangular in shape and on the front end of which the spray head 11 is mounted. The spray head consists of a casing 12 which is preferably rectangular and box shape in construction, and which extends across and is longitudinally secured to the base plate 10 by bolts 13. The interior of the casing 12 constitutes a large cylindrical chamber 14, the lower side of which opens through a hole 15 in the lower wall of the casing into a port 16 in a fitting 17 extending through the base plate 10. Formed in the front wall of the casing 12 and adapted to discharge pressure fluid such as compressed air in small streams from the chamber 14 are a plurality of restricted air ports or orifices 18. These ports are arranged in a group at equal distances about a central conical opening 19. The rear wall of the casing 12 is formed with a large conical opening 20 in alignment with the opening 19.

Extending through the chamber 14 and having its opposite ends fitting tightly into the openings 19 and 20 and its front and rear surfaces flush with the front and rear outer surfaces of the casing 12 is a conical block 21 having a plurality of small longitudinal passages 22 extending therethrough. In the present instance, four passages 22 are provided which diverge rearwardly so that the front ends of said passages are closely spaced together and the rear ends of said passages are spaced relatively far apart.

Secured to the rear wall of the casing 12 is a plate 23 having tapped holes 24 spaced apart to open next to the rear ends of the passages 22. A plurality of paint conduits 25, one for each passage 22 and opening thereto, are threaded into the holes 24, and are provided with hose attaching nipples 26.

A front plate 27 is secured to the base plate 10 and fits tightly against the front of the casing 12. The front plate is formed with a cylindrical chamber 28 in its inner surface, and is provided with a paint nozzle 29 having a restricted jet passage 30 opening centrally

therethrough. A plurality of small ports or orifices 31 are formed in the front wall of the chamber 28 about the jet passage 30. The inner end of the nozzle 29 is provided with a peripheral flange 32 which fits tightly over the ports or orifices 18 in the front wall of the casing 12 and which serves to seal said orifices against the flow of pressure fluid therethrough. The inner end of the jet passage 30 is flared to provide an enlargement communicating with all of the passages 22 extending through the frustrated cone 21.

The chamber 28 communicates through a hole 33 in its lower wall with a passage 34 in a vertical extension 35 of the front end of the fitting 17 extending through the base plate 10. A valve member 36 having a diametrical passage 37 and an operating lever 38 is rotatably mounted in the fitting 17 between the passages 16 and 34, and is adapted to cut off the supply of pressure fluid to the chamber 28.

A vertical bracket in the form of a plate 39 is rigidly secured to the rear end of the base plate 10, and is formed with a centrally depending lug 40 having an aperture 41. Extending through the aperture 41 in which it is clamped and beneath the base plate 10 to the fitting 17 into the rear end of which it is threaded is a pipe 42 which forms part of a pressure fluid line adapted to receive compressed air from any suitable source (not shown).

Four paint conduits 43 are rigidly mounted in the bracket 39 above the base plate 10, and are provided at their front and rear ends with hose attaching nipples 44 and 45, respectively. The front nipples 44 are connected by flexible hose 46 to the nipples 26 on the nozzles 25, and the rear nipples 45 are connected to supply hose 47 adapted to receive paints of the same or different colors from any suitable source (not shown). In the present instance the conduits 43 are arranged in two rows, one above the other, so that two of the hose 46 are positioned directly over the other two.

Extending horizontally between the two rows of hose 46 is a clamping member or bar 48 the opposite ends of which are journaled in vertical brackets 49 secured to the sides of the base plate 10, and one end of which is provided with an operating lever 50. The upper ends of the brackets 49 are rigidly connected by a cross bar 51 extending over the hose 46. The proportions are such that upon turning the bar 48 into horizontal position the hose 46 will be permitted to be open, and upon turning the bar into a vertical position, the sides thereof will clamp two hose against the base plate 10 and two hose against the bar 51 to cut off the flow of paint to the spray head 11.

In operation, compressed air is admitted to the casing 12 through the pipe 42 and fit-

ting 17 when the front plate 27 is removed from the top plate 10. The valve member 36 is closed to cut off the supply of compressed air to the passage 34 normally communicating with the chamber 28. Compressed air is forcibly ejected from the casing 12 in small streams through the ports 18, and serves to create a substantial vacuum at the front ends of the passages 22. This vacuum causes the discharge of separate jets of paint from the jet passages. Preferably paints of different colors are supplied to obtain a mottled color effect on the surface being painted.

When the front plate 27 is secured in place the air ports 18 are closed, and the jets of paint from the passages 22 are commingled in the jet passage 30 in the nozzle 29, but are not mixed sufficiently to form a homogeneous mixture. The valve member 36 is opened, and compressed air is discharged through the ports 31 to create a suction at the outer end of the jet passage 30 to induce the flow of paint.

The supply of paint can be cut off when desired by rotating the clamping bar 48 into a vertical position thereby collapsing the hose 46 against the base plate 10 and the cross bar 51.

It is frequently desirable to spray unequal amounts of differently colored paints or of different substances. Thus when dark and light paints are used, less dark paint is required than light paint. Unequal amounts of the differently colored paints can be sprayed by providing a conical block 21 having differently sized passages 22 or by providing hose 46 having differently sized passages. The relative amount of differently colored paints can be varied by substituting blocks 21 with different passages 22 or by substituting hose 46 having different sized passages, or both.

It will be evident that I have provided a spraying device which is adapted to spray a variety of different colored paints or other substances in a plurality of independent jets upon a surface. In spraying the substances in separate jets, only a partial mixing thereof takes place and consequently a mottled color appearance is obtained. Where less contrast is desired, the jets of substance can be partially mixed in a discharge nozzle into which they are directed. The construction is simple and inexpensive, and the device is easy to operate and convenient to use.

I claim as my invention:

1. A spraying device having, in combination, a base plate, a casing mounted on one end of said base plate, a truncated cone extending through said casing and having a plurality of passages converging closely together at the front end, said casing having a plurality of ports formed in its front wall about the front end of said cone, means for supplying the material to be sprayed to said pas-

sages, and means for supplying pressure fluid to said casing.

2. A spraying device having, in combination, a base plate, a casing mounted on one end of said base plate, a truncated member extending through said casing and having a plurality of separate passages converging toward the front end, said casing being formed in its front wall about the front end of said member with pressure fluid discharge means, individual pipe lines for supplying the material to be sprayed to said passages, and means for supplying pressure fluid to said casing.

3. A spraying device having, in combination, a spray head comprising a casing, a truncated cone extending through said casing and having a plurality of conically rearwardly divergent passages opening at opposite ends thereof, and pressure fluid discharge means in the front wall of said casing about the front end of said cone.

4. A spraying device having, in combination, a support, a nozzle member mounted on said support and having a plurality of spaced separate passages converging at the front end thereof, separate means one for each passage for supplying the materials to be sprayed to the rear ends of said passages, and means for discharging pressure fluid about the discharge ends of said passages as a group at the front end of said nozzle member to induce a flow of said materials therethrough.

5. A spraying device having, in combination, a support, a casing mounted on said support, a nozzle member extending through said casing and having a plurality of passages converging closely together at their front ends, a plate fitting against the rear end of said casing and said nozzle member, a plurality of conduits supported by said plate for supplying paint to said passages, a hollow plate secured next to the front of said casing, a nozzle mounted in said last mentioned plate and communicating with said passages, said last mentioned plate having a plurality of ports opening about said nozzle, means for supplying the material to be sprayed to said conduits, and means for supplying pressure fluid to said ports.

6. A spraying device having, in combination, a support, a casing on said support, a member in said casing having a plurality of passages for discharging separate jets of paint therefrom, a plurality of ports in said casing and about said passages, means for supplying material to be sprayed to said passages, a removable plate mounted next to said casing, said plate having a paint nozzle communicating with said passages and closing said ports, and having a plurality of ports opening about said nozzle, and means for supplying pressure fluid to either of said sets of ports.

7. A spraying device having, in combina-

tion, a support, a casing on said support, a member in said casing having a plurality of passages for discharging separate jets of paint therefrom, means formed in said casing and about said passages for discharging pressure fluid, means for supplying paint to said passages, and a removable supplemental casing mounted next to said first mentioned casing, said supplemental casing having a paint nozzle communicating with said passages and closing said first mentioned means, and being formed with means opening about said nozzle and for discharging pressure fluid, means for supplying pressure fluid to both casings, and valve means for cutting off said supply of pressure fluid to said supplemental casing.

8. A spraying device having, in combination, a support, a spray head on said support having a plurality of jet passages and a plurality of restricted pressure fluid ports associated with said passages, a removable front plate having a small jet passage communicating with the discharge ends of said passages and having a plurality of restricted ports associated with its passage, means for supplying material to be sprayed to said first mentioned jet passages, and means for supplying pressure fluid to either of said sets of ports.

9. A spraying device having, in combination, a spray head having a plurality of separate passages for discharging independent jets of materials, a removable supplemental spray head secured to said first mentioned head and having a passage, said first mentioned passages opening into said last mentioned passage, and means for inducing a flow through the last mentioned passage and said first mentioned passages.

10. A spraying device having, in combination, a support, a spray head on said support having a plurality of jet passages, a supplemental spray head having a jet passage communicating with said jet passages and having pressure fluid discharge means associated with its jet passage, means for supplying materials to be sprayed separately to said first mentioned jet passages, and means for supplying pressure fluid to said discharge means.

11. A spraying device having, in combination, a support, a casing on said support, means extending through said casing and defining a plurality of passages converging closely together at their front ends, individual means one for each passage for supplying the material to be sprayed to said passages, a mixing chamber opening to the discharge ends of said passages, a single discharge passage opening from said mixing chamber, and means for discharging pressure fluid from said casing about said last mentioned passage.

12. A spraying device having, in combination, a support, a spray head on said support having a plurality of jet passages and means

for directing pressure fluid outwardly about said jet passages, a removable front plate having a small jet passage communicating with the discharge ends of said passages and having means for directing pressure fluid outwardly about said jet passage, means for supplying material to be sprayed to said first

mentioned jet passages, and means for supplying pressure fluid to either of said two first mentioned means.

10

In testimony whereof, I have hereunto affixed my signature.

ARNOLD H. HOTTINGER.
